E. H. ANGIER

CRÉPING PAPER

Filed June 21, 1921

Fig. 2.

Fig. 1.

Inventor:

Edward H. Angier,
by *Henry Smith*

UNITED STATES PATENT OFFICE.

EDWARD H. ANGIER, OF FRAMINGHAM, MASSACHUSETTS.

CRÉPING PAPER.

Application filed June 21, 1921. Serial No. 479,405.

To all whom it may concern:

Be it known that I, EDWARD H. ANGIER, a citizen of the United States, and a resident of Framingham, county of Middlesex, and 5 State of Massachusetts, have invented an Improvement in Crêping Paper, of which the following description, in connection with the accompanying drawings, is a specification, like characters on the drawings representing like parts.

This invention relates to the production of crêped or crinkled paper and the object is to provide a method and mechanism whereby crinkled paper of superior quality may 15 be effectively produced.

My invention will best be understood by reference to the following description of specific embodiments thereof shown by way of example in the accompanying drawings, 20 wherein:

Fig. 1 is a diagrammatic view of a crêping machine; and

Fig. 2 is a similar view of a modification.

My invention may be practiced by a suitable arrangement of crêping mechanism which generically is of the well known roll and doctor type wherein a moist web is caused to adhere to a suitable supporting surface, usually a smooth surfaced roll 5 known as the crêping roll, and removed therefrom by a blunt edged abutment or doctor blade 7 which crowds the moist stock back upon itself and crêpes it, the moist crêped stock passing to a drier, not shown, 30 where it is dried and the crinkles made permanent. Referring to Fig. 1, I have there shown a machine of this type adapted to operate on suitable finished paper and embodying a saturating tank 9 and a stack of rolls 40 which may include a roll 11 rotating in the bath in the tank 9, the crêping roll 5 above the roll 11 and a soft surfaced squeeze roll 13 pressing down on the crêping roll 5. A web of paper *a* may be led from a supply 15 over suitable guiding means 17 in the bath to the lower surface of the roll 11, passes around the same and between the roll 11 and the crêping roll 5, around the crêping roll 5 under the squeeze roll 13 where the surplus

50 moisture is squeezed out and allowed to gravitate back to the tank 9 and thence to the doctor blade 7 where it is crêped. The crêping roll 5 preferably is heated, as by steam admitted internally through pipe 19.

55 In accordance with my invention a more effective crêping is provided for by confining

the moist web *a* to the crêping roll 5 by a relatively impermeable overlying layer and in particular the pressure of the squeeze roll 13, which serves to distribute the saturating liquid through the fibers of the web *a* and to squeeze out the surplus moisture, may be applied thereto through such an impermeable layer. This layer may, according to one embodiment of the invention, be of what is 60 known as duplex paper, that is, a waterproof paper product consisting of two thicknesses of paper united by an intervening waterproofing adhesive which is preferably what is known as black asphalt, that is, the 65 pitchy residue of oil distillation.

In the example of my invention shown in Fig. 1 I have graphically illustrated the use of a duplex web by showing such a web as if manufactured as utilized in the crêping 70 operation, a proceeding possible although by no means necessary. Thus, referring to the drawings, I have shown a supply roll 21 from which the paper web *b* is led over coating roll 23 which coats one side of it with asphalt and it is then led to the squeeze rolls 25 and there the web *c* led from the supply roll 27 is superposed thereon and the two are firmly pressed together to form the duplex web *bc* consisting of the two separate webs 80 of paper *b* and *c* united by the intervening layer of asphalt and forming a substantially impermeable compound web.

The duplex web *bc* may be led to the saturating bath 9 over suitable guide means 17 90 therein which are preferably so arranged that the web *bc* will be separate from the web *a* through a part of its passage through the bath. The web *bc* is then led to the roll 11 in such a manner that it will overlie the 95 web *a* on the crêping roll 5 and be interposed between the web *a* and the squeeze roll 13. Thus in the form of the machine shown it lies inside the web *a* on the roll 11 and outside the same on the crêping roll 5. The duplex web *bc*, which is softened in the bath, is crêped by the doctor 7 together with and simultaneously with the web *a* and may pass therefrom to the drier and there be dried, the product then being the crêped web *a* and 100 a crêped duplex web *bc*, the crêped duplex paper being in itself a desirable article of manufacture.

It has been demonstrated empirically that when a web of paper is thus crêped after 110 being pressed against the crêping roll by an overlying web of duplex paper that the

characteristics of the resultant crêped material is markedly different from those which result when paper is crêped alone in the usual manner. The crêpings or crinklings are much sharper and more clean cut. The reason for this is necessarily a matter involving a certain amount of speculation and I do not wish to be bound to any particular theory of operation. I shall, however, state what appears to be the probable cause of this result.

The crêping action depends upon the proper conditioning of the stock in the bath 9 and its adherence to the crêping roll 5 in such manner that it will not be merely stripped therefrom by the doctor blade 7 but crowded back upon itself and crêped. Thus, to increase the adherence of the web to the crêping roll it is not unusual to employ sizing in the bath 9. The squeeze roll 13 squeezes out the excess moisture and presses the moist stock into close adherence with the roll 5. If adhesive is used the stock tacks to the roll effectively particularly when the latter is steam heated as herein indicated by the steam pipe 19. It will be obvious that as the web *a* with an impermeable layer over the same passes under the squeeze roll 13 the water cannot pass out through this impermeable layer. The action of the squeeze roll, therefore, presses the water throughout the fibers of the paper and results in a much more uniform conditioning of the same in that all parts are thoroughly though not excessively saturated and the adhesion thereof to the roll is thus made uniform throughout the extent of the web. Whether this theory of action is correct or no, as I have stated it is practically demonstrated that the crêping effect on the web *a* is markedly different from that which would be effected were the impermeable overlying layer absent.

In Fig. 1 I have described the impermeable layer as consisting of a waterproof or duplex paper which is crêped together with the web *a* and utilized itself as a product of the machine. Obviously other impermeable materials might be used and also, whether such other materials, as for example sheet rubber, or waterproof papers are utilized, they may within the scope of my invention be applied otherwise than as in the modification illustrated in Fig. 1 wherein there is used an impermeable web of the same extent of area as the web *a* to be crêped. Thus, referring to Fig. 2, I show the crêping of the web *a* in connection with an impermeable layer 29 in the form of an endless belt, part of which leads in an S-like form around the roll 11 and the crêping roll 5 in such manner as to overlie the moist stock on the latter. After the same has passed the doctor it is led upwardly over suitable guide rolls 31 and back to the front side of the roll

11. If duplex paper or like material is used for the belt 29 it may be permitted to crêpe at the doctor 7 and suitable squeeze rolls 33 may act upon the same to flatten out and smooth the crêpings so that it may as it 70 passes to the crêping roll again lie smoothly on the web *a* and press it firmly and uniformly against the crêping roll 5.

The form of the invention shown in Fig. 1 also serves as a partial illustration of the 75 invention particularly described and claimed in my copending application Serial No. 479,404, filed June 21, 1921.

Having thus described in detail the particular embodiments of my invention shown 80 by way of example in the accompanying drawings, what I claim as new and desire to secure by Letters Patent I shall express in the following claims.

Claims.

1. The method of crêping paper comprising depositing moist stock on a smooth surfaced roll, depositing a separate impermeable band over the stock, pressing both into close adherence with the roll and crowding 90 the stock back on itself while adhering to said roll.

2. The method of crêping paper comprising depositing moist stock on a smooth surfaced roll, depositing a moist duplex waterproof stock thereover, pressing both into close adherence with the roll and crowding 95 them back on themselves while adhering to said roll.

3. The method of crêping a moist web 100 with a doctor characterized by superposing a duplex waterproof web on another web on the stock supporting surface.

4. The method of crêping a moist web 105 with a doctor characterized by operating on a plurality of webs disconnected throughout their width the outer of which is impermeable.

5. The method of crêping a moist web 110 with a doctor characterized by confining the moist stock to be crêped to the stock supporting surface by an independent overlying impermeable layer.

6. The method of crêping paper by roll and doctor characterized by pressing moist stock to the roll under an independent overlying impermeable band.

7. The method of crêping paper by roll and doctor characterized by circulating an impermeable belt over the roll to confine 120 moist stock thereto.

8. Crêping mechanism comprising a supporting surface for moist stock, a cooperating abutment for stripping the stock from the surface and an impermeable layer separate from and disconnected from the stock to confine the stock to the surface.

9. Crêping mechanism comprising a supporting surface for moist stock, a cooperating abutment for stripping the stock from 130

the surface, means for pressing the stock against such surface and an impermeable confining layer separate from and disconnected from the stock through which the pressure is exerted on the stock.

10. Crêping mechanism comprising paper saturating means, a crêping roll and its doctor, a cooperating squeeze roll and an independent impermeable layer overlying

10 the paper on the crêping roll.

11. Crêping mechanism comprising paper saturating means, a crêping roll and its doctor, a cooperating squeeze roll and a circulating impermeable belt passing under the

15 squeeze roll to confine the paper thereto.

12. Crêping mechanism comprising a stack of rolls, a doctor cooperating with an intermediate roll, and an independent impermeable strip trained through the rolls

20 and leading about said intermediate roll to the vicinity of the doctor to confine stock thereto.

13. Crêping mechanism comprising a stack of rolls, a doctor cooperating with an

25 intermediate roll, and an independent im-

permeable strip trained in the path of the stock through said stack to confine the stock to said intermediate roll.

14. Crêping mechanism comprising a crêping roll, a doctor cooperating therewith and an impermeable circulating belt having a portion overlying an extended arc of said roll which terminates adjacent the doctor to confined stock thereto.

15. The method of crêping a moist web 35 with a doctor characterized by simultaneously operating on a plurality of disconnected, independent webs the outer one of which is of material to retain the inner one in close adherence with a supporting surface.

16. The method of crêping a moist web with a doctor characterized by confining the moist stock to be crêped to the stock supporting surface by a separate, disconnected 45 overlying layer.

In testimony whereof, I have signed my name to this specification.

EDWARD H. ANGIER.
